[57] CLAIM

The ornamental design for a novelty cap, as shown and described.

DESCRIPTION

FIG. 1 is a perspective view of a novelty cap showing my new design;

FIG. 2 is a top plan view thereof;

FIG. 3 is a right side elevational view, the left side being a mirror image thereof;

FIG. 4 is a front elevational view thereof;

FIG. 5 is a rear elevational view thereof;

FIG. 6 is a bottom plan view thereof;

FIG. 7 is a perspective view of a novelty cap showing a modified form of my new design;

FIG. 8 is a top plan view thereof;

FIG. 9 is a right side elevational view, the left side being a mirror image thereof;

FIG. 10 is a front elevational view thereof;

FIG. 11 is a rear elevational view thereof; and

FIG. 12 is a bottom plan view thereof.

FIG. 13 is a perspective view of a novelty cap showing another modified form of my new design;

FIG. 14 is a front elevational view thereof;

FIG. 15 is a perspective view of a novelty cap showing yet another modified form of my new design; and

FIG. 16 is a front elevational view thereof.
